[57] **CLAIM**

The ornamental design for a combined slide hammer nail puller and building wrecking tool, as shown and described.

DESCRIPTION

FIG. 1 is a side elevational view of a combined slide hammer nail puller and building wrecking tool showing my new design;

FIG. 2 is a front elevational view thereof;

FIG. 2A is a horizontal sectional view thereof taken downwardly along line 2A—2A of FIG. 2;

FIG. 3 is a top plan view of FIG. 2;

FIG. 4 is a horizontal sectional view taken downwardly along line 4—4 of FIG. 1; and

FIG. 5 is a bottom plan view of FIG. 4.
